UNITED STATES PATENT OFFICE.

CARL HENRY EPPLER, OF OAKLAND, CALIFORNIA.

SANITARY BOTTLE-CLOSER.

1,094,784.

Specification of Letters Patent. Patented Apr. 28, 1914.

Application filed January 18, 1913. Serial No. 742,915.

To all whom it may concern:

Be it known that I, CARL HENRY EPPLER, a citizen of the United States, residing at Oakland, in the county of Alameda, and 5 State of California, have invented certain new and useful Improvements in Sanitary Bottle-Closers, of which the following is a specification.

This invention relates to cap openers for 10 bottles and is particularly designed for use in connection with milk bottles where paper caps or closures are used.

It is one of the objects of my invention to provide an opener which is designed to 15 lie beneath the cap and upon the usual bottle shoulder or ledge at the mouth of the bottle, with a portion projecting between the edge of the cap and the mouth of the bottle and adapted to be grasped by the 20 user when it is desired to remove the cap.

A special feature of my invention consists in so forming the opener that it will 25 not tear off when a pull is exerted and which will not in any way mutilate the integrity of the peripheral edge of the cap or closure.

The device of my invention will be more 30 fully disclosed in connection with the accompanying drawing and will be more particularly pointed out in and by the appended claim.

In the drawing:—Figure 1 is a perspective view of a bottle showing the device 35 of my invention applied thereto. Fig. 2 is a vertical sectional view thereof. Fig. 3 is a perspective view of the device of my invention detached from the bottle.

Like characters of reference designate 40 similar parts throughout the different figures of the drawing.

As shown, the bottle is indicated at 1 and 45 is provided with the usual shoulder or ledge 2 at the mouth thereof. A cap or closure 3 is shown in a closed position upon the ledge of the mouth of the bottle.

In the most preferred embodiment of my 50 invention the same consists of a strand of material of a wire-like nature which is preferably non-metallic. The strand, as shown, forms a rectangular frame having side par-

allel frame portions 4 adapted to extend 50 beneath the cap 3. The looped end or bight 5 forms one end of the frame and the free ends 6 are bent as shown in Fig. 3 to form the other end of the frame. Tabs 7, preferably of any flexible material, are 55 looped about the ends of the frame to inclose the same.

A sheath 8 extends about the frame and the ends of the sheath are connected by a line of stitching 9 or in any other suitable manner. The sheath 8 is preferably of waxed paper. The ends of the frame inclosed by the tabs rest upon the shoulder or ledge 2 of the bottle and the cap 3 is pressed into position upon the frame with the tabs 7 60 65 projecting, as shown in Fig. 2. The frame is substantially rigid so that when a pull is exerted on one of the tabs the resulting lift is spread across a relatively considerable area of the paper cap so as not to mutilate 70 the same. Furthermore, the end of the frame, remote from the tab pulled, acts as a fulcrum about which the cap and frame are raised.

By preserving the integrity of the cap, 75 the same can be effectively reused in cases where a portion of the contents of the bottle is not removed therefrom.

While I have herein shown and described 80 one specific embodiment of my invention, I do not wish to be limited thereto except for such limitations as the claim may import.

I claim:—

The combination with a bottle and a closure cap therefor, of an opener for the cap, 85 comprising a substantially rigid frame composed of parallel bars extending beneath the cap, a tab connected with said bars and projecting above the cap, and a sheath disposed about said bars, substantially as described.

In testimony whereof I affix my signature in presence of two witnesses.

CARL HENRY EPPLER.
